(57) **CLAIM**

The ornamental design for a loudspeaker, as shown and described.

DESCRIPTION

FIG. 1 is a perspective view of the front left side of a loudspeaker showing my new design.

FIG. 2 is a perspective view of the bottom of the loudspeaker of FIG. 1.

FIG. 3 is a perspective view of the rear bottom of the loudspeaker of FIG. 1.

FIG. 4 is an orthogonal view of the left side of the loudspeaker of FIG. 1, the right side being a mirror image thereof; and,

FIG. 5 is an orthogonal view of the top side of the loudspeaker of FIG. 1.

1 Claim, 5 Drawing Sheets
